UNITED STATES PATENT OFFICE.

HERBERT W. COWAN, OF HOLYOKE, MASSACHUSETTS, ASSIGNOR TO WHITE & WYCKOFF MFG. CO., OF HOLYOKE, MASSACHUSETTS, A CORPORATION OF MASSACHUSETTS.

DESIGN FOR A DISPLAY-STAND.

49,795.

Specification for Design.

Patented Oct. 24, 1916.

Application filed May 16, 1916. Serial No. 97,936. Term of patent 3½ years.

To all whom it may concern:

Be it known that I, HERBERT W. COWAN, a citizen of the United States, residing at 16 Hitchcock street, in the city of Holyoke, in the county of Hampden and State of Massachusetts, have invented a new, original, and ornamental Design for Display-Stands, such as are employed for supporting articles in show-windows, on store-counters, and elsewhere.

The design is well shown in the accompanying drawing in which—

I claim:

The ornamental design for a display stand, as shown.

HERBERT W. COWAN.
